UNITED STATES PATENT OFFICE.

MAX P. BERNHAGEN, OF MILWAUKEE, WISCONSIN.

LEATHER-CUTTING MACHINE.

1,159,161.

Specification of Letters Patent. Patented Nov. 2, 1915.

Application filed June 17, 1914. Serial No. 845,631.

To all whom it may concern:

Be it known that I, MAX P. BERNHAGEN, a citizen of the United States, residing at Milwaukee, in the county of Milwaukee and State of Wisconsin, have invented certain new and useful Improvements in Leather-Cutting Machines, of which the following is a specification.

This invention relates to leather cutting machines, and one of the principal objects of the invention is to provide a machine of simple construction which will quickly cut leather of varying thicknesses into various shapes to be used for various purposes, and means being provided for quickly adjusting the cutter relatively to the cutting block.

Another object of the invention is to simplify this invention of leather cutting machines of this character and render the machine more reliable and efficient in use.

These and other objects may be attained by means of the construction illustrated in the accompanying drawings, in which,

Figure 1 is a side elevation of a leather cutting machine made in accordance with this invention, Fig. 2 is a horizontal sectional view taken through the standard at the pivotal point of the rocker arms, Fig. 3 is a sectional view of the cam-shaft and the adjacent part being shown in elevation, Fig. 4 is a detail view of the clutch, and Fig. 5 is a sectional view showing the manner of securing the cutter to the standard.

Referring to the drawings, the numeral 1 designates a post or upright, and supported upon the post at the top is a motor 2; and extending from front to rear through the post 1 is a slot or opening 3, and pivotally mounted upon a bolt 4 extending at right angles to the slot 3 is a rocker arm 5. Secured to and extending rearwardly from the post 1 are bearing brackets 6, and journaled in said brackets is a cam-shaft 7 carrying a centrally disposed cam 8, said cam being in vertical alinement with the rocker arm 5 and underneath the same.

Connected to the outer end of the rocker arm 5 is a pulley wheel 7, and an operating belt secured over the pulley wheel and over the pulley wheel on the armature shaft 2^a of the motor 2 providing means for operating the device.

Connected to rear end of the rocker arm 5 is a bracket 9 through which an adjusting screw 10 extends, said screw engaging a wedge 11, provided with a metal bearing

portion 12 for the cam 8. The wedge 11 is adjustable longitudinally of the rocker arm 5 to regulate the throw of the same by means of the screw 10. A slot 13 is formed in the rear end of the rocker arm 5 and a bearing screw 14 extends through the slot and bears against the top of the wedge 11 to hold the latter firmly in adjusted positions.

Firmly connected to the front end of the rocker arm 5 are forked members 16 which extend into and through recesses 17 formed at opposite sides of a standard 18, said standard being mounted in a guide ring 19 secured at its inner end to the post 1. A similar guide member 20 is mounted near the lower end of the standard 18 and secured to the post 1. The lower end of the standard 18 is mounted upon the screw 21 extending through a bracket 22 and provided with a ball 23 upon its upper end which fits within a socket in the lower end of the standard 18. On the forked members 16 is one ball bearing *a* on each side and said balls are mounted in slots 25 in the sides of the recesses 17.

Connected to the standard 18 by means of clamp members 26 and a bolt 27 is a pressure plate 28 having a flat bottom surface of any suitable contour and having secured thereto the cutters 28^a of different kinds.

The cutting block 29 is mounted on a table or support 30, said block being held firmly in place by means of binding screws 31 in the usual or any suitable manner.

Depending from the lower side of the table 30 is a bracket 32 and pivotally connected at 33 to said bracket is a link 34 which is pivoted at 35 to a foot pedal 36. The pedal 36 is provided with a spring 37 to raise it to its normal position after each operation, and said pedal is pivoted at 38 to a bracket 39 supported upon the base 40. A connecting rod 41 engages the foot pedal 36 at one end while the opposite end is connected to a lever 32 pivoted at 33 to a yoke 44 which engages a clutch member 45 on the outer end of the cam-shaft 7. The movement of the foot pedal 36 throws the clutch member 45 into engagement with the clutch member 46 to rotate the belt-pulley 47. A spring 48 returns the rocker arm 5 to its original position after each operation.

The operation of the invention may be briefly described as follows: The rotation of the cam 8 underneath the wedge 11 forces

the forked ends 16 of the rocker arm 5 downward against the tension of the spring *a*, to force the cutter 28^a carried by the pressure plate 28 against the upper surface of the block 29 to cut a piece of leather placed between the said block and cutter carried by the presser plate, and when the foot is removed from the pedal 36, the spring 48 returns the rocker arm 5 to its original position and owing to the ball bearings *a* operating in the slots 25, the standard 18 is turned slightly to move the presser plate 28 out of vertical alinement with the cutter block 29.

15 From the foregoing it will be obvious that a leather cutting machine made in accordance with this invention is comparatively simple in construction, is quick in operation, and cannot readily get out of order.

20 Various changes may be made in the details of construction without departing from the spirit and scope of the invention as defined in the claims.

What is claimed is:—

- 25 1. A leather cutting machine comprising a base, a vertical standing upright secured to said base, a pair of spaced brackets secured on the rear face of said base intermediate its end, said upright provided with a transversely extending slot adjacent its upper end thereof, a rocker arm pivoted in said slot of the upright, a cam shaft mounted in the bracket, a cam on said shaft, means on the under surface of the rocker arm to be engaged by the cam for operating the same, guide arms secured to the forward end of said rocker arm, guide rings secured to the front face of said upright and positioned one above the other, a standard slidably mounted in said guide rings, said standard being supported by the bracket in the rocker arm, a pressure plate adjustably secured to the standard and means mounted on the upper end of a post and connected to the shaft for operating the same.
- 30 2. A leather cutting machine comprising a vertical standing upright, a pair of brackets secured on the rear face of said upright, a rocker arm extending through said upright adjacent its upper end, a cam shaft 50 mounted in said bracket, a drive wheel carried on one end of said shaft, a cam carried by the shaft, a motor on the upper end of said upright, connections between the drive wheel of the shaft and the motor for operating the same, guide rings mounted on the front face of said upright, a bracket secured to the forward end of the rocker arm, a standard slidably mounted between the guide rings and supported by the brackets 55 of the rocker arm, a pressure plate adjustably secured to the standard adapted to be moved upwardly and downwardly upon the rotation of the motor.

3. A leather cutting machine comprising 65 a base, a vertical standing post upright on said base, said upright provided with a transverse slot through its upper end, a rocker arm mounted through said slot, pivotally mounted in said slot, brackets secured to the rear face of said upright, a shaft mounted in said brackets, a drive wheel carried on one end of the shaft, a cam mounted centrally of said shaft adapted to engage the under surface of the rocker arm, 70 a motor positioned on the upper face of said post connecting the motor to the drive wheel of the cam shaft for rotating the same, a pair of arms secured to the outer end of the rocker arm, guide rings positioned one 75 above the other and secured to the upright at the front face thereof, a standard slidably mounted through said guide rings and supported therebetween by the arms on the rocker arm, a pressure plate adjustably 80 mounted to the standard, means secured to the under surface of the standard for holding the same in a normal position, means connected to the cam shaft for throwing the same into and out of engagement with the 85 motor.

In testimony whereof I affix my signature in presence of two witnesses.

MAX P. BERNHAGEN.
